US00D904288S

(12) **United States Design Patent** (10) Patent No.: **US D904,288 S**
(45) Date of Patent: **** Dec. 8, 2020**

(54) **PHOTOVOLTAIC DEVICE**

- (71) Applicant: **First Solar, Inc.**, Perrysburg, OH (US)
- (72) Inventors: **Benyamin Buller**, Sylvania, OH (US); **Joshua Conley**, Sylvania, OH (US); **Richard S. Malik, Jr.**, Rossford, OH (US); **Brian Maus**, Milan, MI (US); **Thomas Truman**, Toledo, OH (US)
- (73) Assignee: **FIRST SOLAR, INC.**, Perrysburg, OH (US)
- (**) Term: **15 Years**
- (21) Appl. No.: **29/655,237**
- (22) Filed: **Jul. 2, 2018**

Related U.S. Application Data

- (63) Continuation of application No. 29/537,359, filed on Aug. 25, 2015, now Pat. No. Des. 824,847.

(57) **CLAIM**

The ornamental design for a photovoltaic device, as shown and described.

DESCRIPTION

FIG. 1 is a bottom plan view of a photovoltaic device showing our new design;

FIG. 2 is a top plan view thereof;

FIG. 3 front elevational view thereof;

FIG. 4 is a back elevational view thereof;

FIG. 5 is a left side elevational view thereof; and,

FIG. 6 is a right side elevational view thereof.

The broken lines in the figures represent portions of photovoltaic device which form no part of the claimed design.

1 Claim, 2 Drawing Sheets
